UNITED STATES PATENT OFFICE

LOUIS MORRISON, OF NEW YORK, N. Y.

DESIGN FOR A COMBINED DESK STAND AND PENHOLDER OR SIMILAR ARTICLE

Application filed December 13, 1930. Serial No. 37,974. Term of patent 7 years.

To all whom it may concern:

Be it known that I, LOUIS MORRISON, a citizen of the United States of America, residing at New York city, county and State of New York, have invented a new, original, and ornamental Design for a Combined Desk Stand and Penholder or Similar Article, of which the following is a specification, reference being had to the accompanying drawing, forming part hereof, in which—

Fig. 1 is a front perspective view of a combined desk-stand and pen-holder or similar article showing my new design, and Fig. 2 is an end view thereof.

I claim:

The ornamental design for a combined desk stand and penholder or similar article as shown.

Signed at New York city, New York, this 10th day of December, 1930.

LOUIS MORRISON.
